UNITED STATES PATENT OFFICE.

HAROLD V. ATWELL, OF WHITING, INDIANA, ASSIGNOR TO STANDARD OIL COMPANY, OF WHITING, INDIANA, A CORPORATION OF INDIANA.

PREVENTION OF EVAPORATION LOSSES.

Application filed April 1, 1927. Serial No. 180,321.

This invention relates to the prevention of evaporation losses of volatile liquids and particularly hydrocarbons or mineral oils containing volatile fractions.

5 The invention will be readily understood from the following description in conjunction with the accompanying drawings, in which:

Figure 1 is an elevational view of a system of tanks and vapor saving apparatus according to the invention;

Fig. 2 is a sectional view of a control valve;

Fig. 3 is a horizontal section on the line 15 3—3 of Fig. 2; and

Fig. 4 is a horizontal section on the line 4—4 of Fig. 2.

Referring to the accompanying drawings, 5 are tanks such as tanks for gasoline, crude oil or other liquid having volatile constituents which readily vaporize so that a substantial quantity of valuable vapors are expelled from the tank during filling and to a lesser degree when the vapor space is heated by the 20 sun or the heat of the day. From the vapor space of each tank 5, pipes 6 lead to valves 7 which communicate through pipes 8 with a manifold 9. The manifold 9 terminates in the suction side of a pump 10. The outlet of 30 pump 10 communicates to pipe 11 which leads to a gas-holder 12 of conventional or other suitable form. The pump 10 is controlled so as to keep the manifold 9 under a slight vacuum.

35 The valve 7 comprises a chamber 13 into which the pipe 6 communicates. In the upper portion of this chamber is a vertical passage 14 surrounded by a channel 15, adapted to contain sealing liquid. Arranged over the 40 opening 14 is an inverted cup 16, the sides or skirt of which extend downwardly into the channel 15 so as to form a seal with the liquid therein to prevent escape of vapors through the passage 14. Above the cup 16 is arranged 45 a cover 17, which is open to the atmosphere through perforations 18 so that atmospheric pressure acts on the upper side of the inverted cup 16. Sufficient clearance is left above the inverted cup so that it may act as 50 a piston, moving under excess pressure on either side.

The pipe 8 terminates in a horizontal mouth 19 at an intermediate level of the chamber 13 and said mouth is surrounded by 55 a channel 20 adapted to contain sealing liq-

uid. Over the mouth 19 of the pipe 8 is mounted a valve 21. This valve is preferably adapted to be moved to its open and closed position transversely of the pressure thereon, so that its movement may be substantially uninfluenced by excess pressure on either side. For example, the valve 21 may suitably be of semi-cylindrical form, having ends by which it is pivotally mounted in the chamber 13, so that the edges of its wall and ends are normally immersed in the sealing liquid in channel 20 so as to prevent communication between pipes 6 and 8. The channel 20 is deeper on one side to permit opening of the valve 21 and is shallower on the other side to provide an abutment therefor. Near one edge of the cylindrical part of the valve 21 is attached a cord, or chain 22. The cord 22 passes under a roller 23 mounted on a spindle supported within the chamber 13 and is connected to the underside of inverted cup 16 so that the valve 21 closes the mouth 19 of the pipe 8 when the inverted cup 16 is in its lowest position. The valve 21 is provided with a weight 24 or other suitable means for causing it to tend to remain closed.

The tanks 5 are provided with the usual means for supplying and withdrawing oil and vacuum relief vents to admit air, hydrocarbon or other gases when an excessive vacuum occurs therein (not shown).

The operation is as follows: Assuming the parts of the valve 7 to be in the positions shown in Fig. 2, and the pump 10 operating to maintain a slight vacuum in manifold 9. If the pressure in one of the tanks increases, due to feeding oil into it or other cause, so that the pressure of the vapor space acting upwardly on the underside of inverted cup 16 exceeds the atmospheric pressure acting downwardly on the upper side of said cup by an amount sufficient to raise said cup, valve 21 and weight 24, the cup 16 will ascend and cause the valve 21 to open, whereupon the pump 10 will withdraw vapors from the tank 5 until the excess pressure therein over atmospheric falls so that the inverted cup 16 is no longer maintained in its elevated position but falls, releasing the tension on the cord 22 so that the weight 24 causes the return of the valve 21 to its closed position.

As will be readily understood, the excess pressure of the tank over atmospheric, at which the valve 21 opens, depends upon the

mass of the inverted cup 16, the valve 21 and weight 24 and the effective area of the inverted cup 16. It will be readily understood that by adjusting these factors, the pressure difference at which the valve 21 opens can be accurately predetermined. The opening of valve 21 is uninfluenced by the degree of pressure on either side thereof and is controlled exclusively by the difference between atmospheric and storage tank pressures.

While the invention has been described in connection with a specific form and application thereof, it must be understood that the invention is not intended to be limited thereby, except by the terms of the appended claims.

I claim:

1. A valve structure comprising a chamber, a conduit leading into said chamber, an outlet from said chamber, vertical walls around said outlet forming a channel for sealing liquid, an inverted cup over said outlet having a skirt depending into said channel, a second outlet from said chamber, a liquid-sealed semicylindrical valve axially mounted to control said second outlet, and means connecting said inverted cup to said valve to effect operation thereof from the movement of the inverted cup.

2. A valve structure comprising a chamber, a conduit leading into said chamber, an outlet from said chamber, vertical walls around said outlet forming a channel for sealing liquid, an inverted cup over said outlet having a skirt depending into said channel, conduit means extending partly into said chamber so as to constitute therearound a channel for sealing liquid, a pivoted valve over said conduit with sides extending into said channel, means connecting said inverted cup to the pivoted valve so as to effect rotation and opening of same when the inverted cup is moved outwardly by excess pressure in the chamber.

3. A valve structure comprising a chamber, a conduit leading thereto, an outlet extending upwardly from the top of said

chamber, vertical walls around said outlet and in spaced relation thereto forming a channel for sealing liquid, an inverted cup having a depending skirt extending into said channel, a conduit leading into the bottom of said chamber and extending thereinto so as to constitute a channel for sealing liquid therearound, a pivoted valve member having sides which extend into said channel, and flexible means connecting said inverted cup to said valve member so that upward movement of the inverted cup causes rotation and opening of said valve member.

4. In combination, a pressure actuated member subjected to atmospheric pressure and a variable vapor pressure, a liquid sealed valve controlling a vapor line and adapted to be operated from the movement of said pressure actuated member, said valve being substantially semicylindrical in shape and pivoted axially so as to be uninfluenced by the pressures on either side thereof.

5. In combination, a pressure actuated member subjected to atmospheric pressure and a variable vapor pressure, a weighted semicylindrical pivoted valve controlling a vapor line, means for maintaining sealing liquid for said valve means operably connecting said member and valve, the opening of said valve being uninfluenced by the pressure thereon on either side thereof and being controlled by the movement of said pressure actuated member.

6. In combination, a chamber, an inverted cup having a skirt depending into sealing liquid and exposed to atmospheric pressure on its upper side and the pressure in said chamber on its underside, an outlet from said chamber, a pivoted cylindrical valve provided with a weight tending to close said outlet and flexible means connecting said inverted cup to said valve, whereby said valve is caused to open when the pressure in the chamber exceeds atmospheric pressure by a predetermined amount.

In testimony whereof I have hereunto set my hand this 14th day of March, 1927.

HAROLD V. ATWELL.
